[57] CLAIM

The ornamental design for an electrical plug body, as shown and described.

DESCRIPTION

FIG. 1 is a top perspective view of an electrical plug body according to our new design;

FIG. 2 is a top plan view of an electrical plug body of our new design shown in FIG. 1;

FIG. 3 is a front side elevational view of the electrical plug body of our new design shown in FIGS. 1-2, with the rear side (not shown) being substantially a mirror image thereof;

FIG. 4 is a bottom plan view of the electrical plug body of our new design shown in FIGS. 1-3;

FIG. 5 is a left end elevational view of the electrical plug body of our new design shown in FIGS. 1-4; and,

FIG. 6 is a right end elevational view of the electrical plug body of our new design shown in FIGS. 1-5.

The broken line showing throughout the drawing figures is included for the purpose of illustrating environmental structure only and forms no part of the claimed design.
